BOOKHOLDER FOR BEDSTEADS

Raymond L. Phillips, Minneapolis, Minn.

Application May 25, 1944, Serial No. 537,240

3 Claims. (Cl. 45—82)

1

This invention relates to new and useful improvements in book holders for bedsteads, and more particularly to such a device having means for supporting a book holder upon the head of a bed or other support whereby a book or magazine supported thereon may be conformably read by a person disposed in a reclining position.

It is well known that when one is in a reclining position as when resting in a bed, that it is rather uncomfortable and fatiguing to manually hold a book in a position whereby the reader may have a clear vision of the printed matter. In other words, to obtain the utmost in comfort the printed matter to be read should, in most cases, be supported a predetermined distance from the eyes. This is more particularly true with a person wearing glasses.

Numerous attempts have heretofore been made to devise some sort of book holder or rack which would be readily positioned on the head piece of a bedstead in such a manner as to support a book or magazine thereon at a desired distance from the reader's eyes, whereby a reader may read in comfort with a minimum of eye strain, and without suffering muscular fatigue, as when a book must be manually held in position for reading.

To the best of my knowledge none of these attempts have proven successful for various reasons such as cost, inconvenience of manipulation, and the inability to support a book in a manner not to obscure too much of the reading matter thereof.

After considerable experimental work in an attempt to eliminate the usual imperfections now prevalent in known devices of this type, I have succeeded in developing a very simple and efficient book holder for supporting a book or other reading material on a bedstead having means whereby it may be quickly adjustably secured to a bedstead in position to support a book at the proper angle relative to the reader's eyes and whereby substantially none of the printed matter of the open pages of the book placed thereon will be concealed, and which is so constructed that the reader, while in a reclining position, may readily vary the angle of the book-supporting frame to accommodate his line of vision and thereby minimize eye strain.

An object of the present invention therefore is to provide a book holder for a bedstead comprising a relatively light inexpensively constructed open book-supporting frame having a centrally disposed frame member, at the opposite sides of which are adjustably mounted a pair of book holders which cooperate with the central frame

2

member to support a book or magazine in an inverted position on the frame.

A further object is to provide a book holder of the class described comprising an open frame having front, rear, and opposed side frame members and a centrally disposed frame member having its ends secured to the front and rear frame members of the frame and disposed in a plane above the median plane of the frame, whereby 5 said centrally disposed frame member may engage and support the central portion of a book, and a pair of book supporting members or rods having their ends slidably engaged with the front and rear frame members whereby they may be 10 laterally adjusted with respect to the central frame member thereby to accommodate the book holder for supporting books of varied sizes and shapes without obscuring any of the printed matter thereof.

20 A further object is to provide a book holder of the class comprising an open book supporting frame including a relatively fixed centrally disposed frame member and a pair of oppositely disposed book holding elements adjustably mounted 25 on said frame, and a rod being slidably supported on the central frame member with its ends intersecting or passing over said book holding elements and cooperating therewith to support the open pages of a book or magazine in a manner 30 whereby the book may readily be read by a person reclining in a bed.

Other objects of the invention reside in the simple and inexpensive construction of the entire apparatus whereby it may readily be manufactured in quantity production with conventional equipment at low cost; in the unique arrangement 35 of the adjustably mounted book holding elements or rods relatively to the centrally disposed frame member, whereby when an open book is placed 40 in an inverted position upon said centrally disposed frame member and book-supporting elements, the open pages of the book will be supported in substantially a given plane, disposed in substantially right angular relation to the line 45 of vision of a person reclining in a bed; in the provision of such a book holder which is so constructed 50 that the reader may readily and conveniently turn the pages of the book without disrupting the position of the book holder nor the position of the book thereon; and in the provision 55 of such a book holder which comprises extremely few parts, is light in weight, and is so constructed whereby the book supporting frame may readily and conveniently be adjusted to any angular position to adapt the book to the line of vision of

the reader, and also whereby the book-supporting frame may be folded into flatwise relation with its supporting means so that the device, when not in use, may readily and conveniently be folded into a relatively small bundle for storage in a small space.

Other objects of the invention will appear from the following description and the accompanying drawings and will be pointed out in the annexed claims.

In the accompanying drawings there has been disclosed a structure designed to carry out the various objects of the invention, but it is to be understood that the invention is not confined to the exact features shown, as various changes may be made within the scope of the claims which follow.

In the drawings:

Figure 1 is a view showing my novel book holder attached to the head of a bedstead;

Figure 2 is a front view of the book holder mounted on a bedstead;

Figure 3 is a sectional view on the line 3—3 of Figure 1, showing the position of a book thereon from the reader's side of the holder;

Figure 4 is a cross-sectional view on the line 4—4 of Figure 3;

Figure 5 is a detail sectional view on the line 5—5 of Figure 2 showing the relative positions of the centrally disposed frame member and the adjustably mounted book holding elements;

Figure 6 is a side view showing the book holder and its supporting frame folded into a small bundle for storage purposes;

Figure 7 is an enlarged detail sectional view substantially on the line 7—7 of Figure 2, showing the preferred manner of securing the ends of the central frame member to the front and rear frame members;

Figure 8 is a similar view on the line 8—8 of Figure 2 showing the preferred manner of slidably securing the ends of the book supporting elements or rods to the front and rear frame members of the supporting frame; and

Figure 9 is a view showing a slightly modified construction.

In the selected embodiment of the invention herein disclosed, there is illustrated in Figures 1 and 2 the head end of a bedstead comprising the usual head board 2 and sides 3 upon which the usual spring, mattress, and bedding are supported in the usual manner.

The novel book holder herein disclosed is shown comprising an open frame, generally designated by the numeral 4, which may be formed of wire or rod and is shown having front and rear frame members or rails 5 and 6, side frame members 7, and a centrally disposed frame member 8, all of which are secured together to provide an integral frame structure.

One of the features of the invention resides in the particular arrangement of the centrally disposed frame member 8 with respect to the front, rear, and side frame members. As best shown in Figure 5, the centrally disposed frame member 8 is preferably located at an elevation above the median plane a—a of the open frame 4, as shown in Figures 5, 7 and 8. This may be conveniently accomplished by welding the terminals of the central frame member 8 to the upper faces of the front and rear frame members 5 and 6, as best shown in Figure 7. By thus securing the ends of the frame member 8 to the front and rear frame members 5 and 6, it provides

a substantial tie therebetween and thereby greatly strengthens the frame.

Another feature of the invention resides in the provision of a pair of book-supporting elements 9 which have their ends slidably engaged with the front and rear frame members 5 and 6, whereby they may be relatively laterally adjusted thereon as indicated by the full and dotted lines in Figure 3, to adapt the holder for supporting books of various sizes.

The book-supporting elements or rods 9 may be mounted on the front and rear frame members 5 and 6 by simply forming terminal eyes 11 therein which encircle their respective frame members 5 and 6, as illustrated in Figure 8. It will also be noted by reference to Figures 5 and 8, that the axes of the book-supporting elements or rods 9 are disposed in a plane below the median plane a—a of the frame 4.

20 The reason for locating the centrally disposed frame member 8 above the median plane a—a of the frame, and the book-supporting elements 9 below the plane a—a, will be best understood by reference to Figure 4. By reference to this figure 25 it will be noted that when a book is supported on the frame, the centrally disposed frame member 8 will be received in the center of the book between the open pages thereof, while the outer marginal edges of the open pages will be supported upon the supporting elements or rods 9 in such a manner that the faces of the open pages will be disposed substantially in a common plane which, when the frame 4 is properly adjusted with respect to the person's eyes, as shown in 35 Figure 1, will be disposed in right angular relation to his line of vision, which is essential to minimize eye strain and to obtain the utmost in comfort when reading in an inclined position.

Another feature of the invention resides in the 40 provision of means for preventing the pages of the book from sagging or dropping out of engagement with the book-supporting elements or rods 9, particularly when a large page is supported on the frame 4.

45 The means provided for thus preventing the pages from sagging or dropping out of engagement with the rods 9 is shown comprising a wire member, which will hereinafter be referred to as the page holder 10. This member is shown secured to a slide 20 mounted for sliding movement on the centrally disposed frame member 8, as indicated by the full and dotted lines in Figure 3. A suitable hand grip 30 depends from the slide 20 whereby it may be conveniently gripped by 50 the reader, as will be understood by reference to Figure 4. The book holder 10 is disposed in cross-wise relation to the frame member 8 and book holding rods 9, and its outer ends are disposed over the rods 9 whereby said ends may be supported on the rods 9 when a book is positioned 55 over the rods 9 when a book is positioned thereon, as shown in Figures 3 and 4.

Means is provided for supporting the frame 4 upon the head 2 of a bedstead and, as here shown, comprises a U-shaped frame, generally designated by the numeral 12, comprising upright legs 13, shown integrally formed with a lower horizontal cross member 14. The U-shaped frame 12 may be simply and economically constructed of a suitable size wire as will readily be understood.

65 Eyes 15 are formed at the upper ends of the legs 13 and are coiled about the rear frame member 6 adjacent to the side frame members 7 of the book holding frame 4, as shown in Figures 1, 2 and 3, whereby the frame 4 is pivotally connected 70 to the supporting frame 12.

Suitable hook elements 16 are shown mounted on the upright legs 13 of the supporting frame 12 and are adapted to engage the upper horizontal edge of the head piece 2 of the bedstead, as shown in Figures 1 and 2. The hooks 16 are so constructed that when in the position shown in Figure 1, they clampingly engage their respective upright legs 13, thereby to support the book holder as a whole in vertically adjusted position on the bedstead. To vertically adjust the supporting frame 12 upon the bedstead, it is only necessary to manually lift the frame upwardly whereby the hooks 16 release their grip on the upright legs 13. The construction of the hooks 16, however, is such that when the upward movement of the frame 12 is interrupted and the frame 12 commences to move downwardly, the hooks 16 will move into clamping engagement with the uprights 13 and thereby secure the supporting frame 12 in adjusted position on the bedstead. Suitable cushion elements 17 are preferably provided at the lower end of the supporting frame 12 to prevent the frame from marring the finish of the bedstead.

To angularly adjust the book-supporting frame 4 upon the upright supporting frame 12, suitable braces 18 are interposed between the upright legs 13 of the supporting frame and the side frame members 7 of the book holding frame 4.

In Figure 1 I have shown the lower ends of the braces 18 pivotally connected to brackets 19, which brackets may be fixedly and permanently secured to the upright legs 13, but not necessarily. If desired, they may be adjustably secured thereto. The upper or opposite ends of the braces 18 are pivotally connected to brackets 21 which are slidably supported on the side rails 7 of the book holding frame 4 and are secured in adjusted positions thereon by suitable wing nuts 22, so located that they may readily be grasped by a person reclining in the bed, as will be understood by reference to Figure 1.

In Figure 9 I have shown a structure in which the centrally disposed frame member 8 has been dispensed with and wherein the book supporting elements 9 have their terminals adjustably engaged with the side frame members 7, and whereby they are disposed in substantially parallel relation to the front and rear frame members 5 and 6. The book or other reading matter is supported thereon in a manner similar to the book shown in Figures 3 and 4.

From the foregoing it will be noted that the novel book holder herein disclosed is extremely simple and inexpensive in construction, and it is so fashioned that it may readily and conveniently be adjusted to any desired position to best accommodate the vision of a person reclining in the bed as indicated in Figure 1, and whereby the reading matter, whether it be a book or magazine, may be positioned at the most desirable angle and distance to afford the most comfortable reading without eye strain.

The page holder 10 is important, as it retains the pages of the book or magazine in flatwise relation whereby they are not likely to sag between the centrally disposed frame member 8 and the book-supporting elements 9. It is slidably mounted on the central frame member 8 to permit the reader to readily shift it from one place to another, as indicated by the full and dotted lines in Figure 3, whereby it may always be positioned so not as to obscure any of the reading matter.

The novel book holder hereindisclosed also permits convenient turning of the pages of a book or

magazine. This may be readily accomplished by simply sliding the book holder 10 out of engagement with the open pages of the book as indicated at P in Figure 3, after which the reader may readily lift one side of the book out of engagement with one of the book holding elements 9 and swing a page downwardly as indicated at N in Figure 4. He may then readily lift the central portion of the book upwardly out of engagement with the centrally disposed frame member 8 and swing the page to be turned over the top thereof, after which the book is again returned to its reading position, shown in full lines in Figures 3 and 4.

To prevent the pages of the book from sagging downwardly, the page holder 10 is returned to a position under the book to support the pages thereof as shown in Figures 3 and 4.

In the drawings I have shown the supporting frame 12 as being supported on the bedstead by the clamping hooks 16. It is to be understood that other forms of clamping devices, applicable for the purpose, may be utilized without departing from the scope of the invention. If desired, a suitable light (not shown) may also be provided on the supporting frame 12 for illuminating the open face of the book or other reading matter.

It will be apparent to those skilled in the art that I have accomplished at least the principal objects of my invention, and it will also be apparent to those skilled in the art that the embodiments herein described may be variously changed and modified without departing from the spirit of the invention, and that the invention is capable of uses and has advantages not herein specifically described; hence it will be appreciated that the herein disclosed embodiments are illustrative only, and that my invention is not limited thereto.

I claim as my invention:

1. In a device of the class described, a U-shaped support having means for securing it to a bedstead whereby it may be vertically adjusted thereon, an open frame pivotally mounted on said support and having front, rear, and opposed side frame members and a centrally disposed frame member, said centrally disposed frame member having its ends secured respectively to the front and rear frame members, rods slidably mounted on said front and rear frame members and movable thereon towards or away from said central frame member and cooperating therewith to support a book, said centrally disposed frame member and said rods being located respectively above and below the median plane of said frame.

2. In a device of the class described, a support having means for securing it to a bedstead whereby it may be vertically adjusted thereon, an open book-supporting frame having front, rear, and opposed side frame members and a centrally disposed frame member, said centrally disposed frame member having its ends secured respectively to said front and rear frame members, means pivotally mounting the rear frame member on said support, means for retaining the frame in angularly adjusted position on the support, a pair of book supporting rods slidably mounted on said front and rear frame members, one at each side of the centrally disposed frame member, said rods being movable towards or away from the central frame member and cooperating therewith to support books of various sizes, and a page holder slidably mounted on the centrally disposed frame member and laterally extending

therefrom and having its terminals engaging said rods.

3. In a device of the class described, an upright support having means for adjustably and removably securing it to a bedstead, an open book-supporting frame having front, rear, and opposed side frame members and a centrally disposed frame member, said central frame member having its ends fixedly secured to the front and rear frame members and whereby it is disposed in a plane above the median plane of the frame, means for retaining the frame in angularly adjusted position on said support, a pair of book supporting members having their ends slidably engaged with the front and rear frame members whereby they may be laterally adjusted with respect to the central frame member to adapt the book supporting frame for supporting books of various sizes, said book supporting members being disposed in a plane below the median plane of the frame, and a page holding rod disposed in crosswise relation to said book supporting members and having a slidable connection with the central frame member whereby it may be longitudinally adjusted thereon, the laterally extending ends of the page

holding rod cooperating with said central frame member and said book supporting members to support the open pages of a book or magazine in substantially a common plane.

RAYMOND L. PHILLIPS.
